ROUNDABOUT

George Henry Pooler, Marietta, Ohio

Application March 1, 1945, Serial No. 580,350

7 Claims. (Cl. 272—33)

1

This invention relates to amusement devices such as are referred to as roundabouts, merry-go-rounds, carousels and the like, and its purpose is to generally, structurally, and otherwise improve upon known pleasure apparatus in this category.

More specifically, the invention pertains to a rotor mounted atop a standard, said rotor being in the nature of a wheel with radial arms or spokes, these being properly interconnected and braced by guy wires, said arms being provided at their outer ends with depending supports and the supports being provided at their lower ends with chairs or the like for the occupants.

In accordance with the principles of the invention the upright or standard structure includes a horizontal friction plate or disc, there being small friction drive wheels in contact with the friction surface thereof, these serving to set the rotor into circular motion, and being mounted on shafts driven either by a motor power means or by foot pedal sprocket and chain means.

Other features and advantages will become more readily apparent from the following description and the accompanying illustrative drawings.

In the drawings, wherein like numerals are employed to designate like parts throughout the views:

Figure 1 is a top plan view of a so-called roundabout constructed in accordance with the principles of this invention, certain of the parts being omitted due to the scale on which the drawing is made, and due to inability to aptly illustrate same on the basis of such scale.

Figure 2 is a central vertical sectional view which brings out all of the details and their association and arrangement.

Figure 3 is an enlarged detail section taken on the vertical line 3—3 of Figure 2, looking in the direction of the arrows.

Figure 4 is a section on the line 4—4 of Figure 2, also looking in the direction of the arrows.

Figure 5 is a fragmentary elevational view showing the foot pedal and crank means, such as is preferably used for propulsion purposes.

Referring now to Figure 2, it will be seen that the upright or standard means comprises an outer tubular standard 7 whose lower end is adapted to be embedded in the concrete foundation or the like. This is provided at its top with an annular plate 8 which serves as a runway. Below this it is provided with a larger plate or table 9 also of annular form which forms a track or runway for propulsion purposes. This is associated with appropriate braces 10 welded or other-

2

wise fastened in place. Telescopically fitted in the standard 7 is an auxiliary or complementary standard 11 which may also be of tubular form and this is secured properly in place and extends well above the plates 8 and 9. The upper extending end is surrounded by a sleeve 12 carrying an outstanding annular plate 13 at its bottom, this being spaced above the plate 8 and provided with anti-friction rollers 14 riding on said plate 8. The plate 13 is also provided with radial sockets 15. Tubular arms 16 are threaded at their inner ends into said sockets 15 and extend radially beyond the series of plates 8, 9 and 13. These arms are provided at their outer ends with depending hanger members 17 and 18 which serve to support the chairs or seats 19 for the users. The upper end of the standard 11 is provided with an extension threaded to accommodate a cap 20 and between this and the upper end of the sleeve 12 is a ball bearing hub unit 21, the parts being held and assembled as shown. The unit 21 is provided with adjustable guy wires or rods 22 which connect at their outer ends to the corresponding outer ends of the radial arms 16. Suitable horizontal marginal reinforcing rods 23 are employed as shown in Figure 1 between the outer ends to distribute stresses and strains and to make the over-all structure sufficiently reliable and sturdy.

Each chair is to be provided with its own propulsion means. It would be quite proper to provide a motor for this but in the present instance I utilize simple pedal-equipped cranks. These cranks are indicated at 24 in Figure 5 and provided with appropriate foot pieces 25, said cranks being mounted in appropriate supports or holders 26. The crankshaft is provided with a sprocket wheel 27. Referring to Figure 3 it will be seen that this sprocket wheel coacts with a companion sprocket wheel 28 on the motion transmitting shaft 29. A sprocket chain 30 is trained over said sprocket wheels. The shaft 29 is journaled in bearings at opposite ends, one bearing assembly indicated as the bracket 31 in Figure 2. There is also an extra bearing equipped bracket or brace 32. Keyed or otherwise mounted on the shaft 29 is a friction driving wheel or disc 33 which rides in contact with the traction surface of the friction plate 9. Thus by pumping the pedal the sprocket mechanism transmits motion to the shaft 29 and its wheel 33 which rides in contact with the plate 9 and drives the rotor and the rest of the parts around in an obvious whirlabout fashion.

I have shown a brake 34 on the shaft 29 and a brake band 35 coacting therewith, said brake

band being controlled by a suitable operating means 36 within convenient operating distance of the occupant of the seat or chair 19.

It is believed that the construction as well as the operation and features and advantages which attend a structure of this type are somewhat self-evident, that is as a result of having considered the description and drawings.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. A roundabout comprising a fixed upright, a sleeve carried on the upper end thereof, a turntable connected to the sleeve, radially disposed arms fixed to the turntable, seats swung from the arms, means whereby the turntable may be manually rotated, a cap rotatably mounted atop the upright and brace rods connecting the cap to the reach end of said arms, a disk fixed upon said upright and upon which the turntable operates, said means including a horizontal shaft, a sprocket wheel fixed thereon, a treadle connected to a seat and having a shaft, a sprocket wheel mounted fixedly on the last shaft, a relatively large friction disk fixed on the upright and a wheel on the first shaft and engaging the large disk, means whereby the occupant of any seat may brake the roundabout, and said last means including a brake drum on the first shaft and a control member depending to the seat.

2. A roundabout comprising a fixed upright, a sleeve carried on the upper end thereof, a turntable connected to the sleeve, radially disposed arms fixed to the turntable, seats swung from the arms, means whereby the turntable may be manually rotated, a cap rotatably mounted atop the upright and brace rods connecting the cap to the reach end of said arms, a disk fixed upon said upright and upon which the turntable operates, said means including a horizontal shaft, a sprocket wheel fixed thereon, a treadle connected to a seat and having a shaft, a sprocket wheel mounted fixedly on the last shaft, a relatively large friction disk fixed on the upright and a wheel on the first shaft and engaging the large disk, and means whereby the occupant of any seat may brake the roundabout.

3. In a device as described a fixed tubular pole, an enlarged plate fixed upon the extreme upper

end thereof, an extension pole mounted within the first pole and projecting through said plate, a sleeve rotatable upon the upper end of the last pole, an anti-friction plate to which the sleeve is fixed, chairs supporting arms fixed to said second plate, said second plate supported by the first plate and antifriction rollers carried by the second plate, means whereby said arms and second plate may be rotated, and means whereby the rotation of the arms may be stopped from any chair.

4. The described device comprising a center pole, radial arms rotatably supported above the pole, chairs depending from the arms and means including drive shafts whereby the device may be manually rotated and means whereby the device may be stopped from any chair, said last means including brake drums on said shafts, and brake control members depending to each chair, said pole having a table fixed on its extreme upper end and a turntable to which the arms are fixed operating on said table, said pole being tubular, another pole mounted in said tubular pole forming an axis for the turntable, and a sleeve mounted rotatably around the last pole and to which the turntable is fixed.

5. The described device comprising a center pole, radial arms rotatably supported above the pole, chairs depending from the arms and means including drive shafts whereby the device may be manually rotated and means whereby the device may be stopped from any chair, said last means including brake drums on said shafts, and brake control members depending to each chair, said pole having a table fixed on its extreme upper end and a turntable to which the arms are fixed operating on said table, and said pole being tubular, another pole mounted in said tubular pole forming an axis for the turntable.

6. The described device comprising a center pole, radial arms rotatably supported above the pole, chairs depending from the arms and means including drive shafts whereby the device may be manually rotated and means whereby the device may be stopped from any chair, said last means including brake drums on said shafts, and brake control members depending to each chair, and said pole having a table fixed on its extreme upper end and a turntable to which the arms are fixed operating on said table.

7. The described device comprising a center pole, radial arms rotatably supported above the pole, chairs depending from the arms and means including drive shafts whereby the device may be manually rotated and means whereby the device may be stopped from any chair, said last means including brake drums on said shafts, and brake control members depending to each chair.

GEORGE HENRY POOLER
